UNITED STATES PATENT OFFICE.

JOSEPH LEDWINKA, OF PHILADELPHIA, PENNSYLVANIA, ASSIGNOR TO EDWARD G. BUDD MANUFACTURING CO., OF PHILADELPHIA, PENNSYLVANIA, A CORPORATION OF PENNSYLVANIA.

AUTOMOBILE DOOR BUFFER.

Application filed October 2, 1924. Serial No. 741,261.

The door buffer of my invention belongs in the field of automobile door buffers and particularly to that portion of the field comprehended by pressed metal door buffer structures. In other words, it is particularly applicable to automobile body door structures made of pressed metal, but it undoubtedly has other applications.

The primary function of such devices is to cushion the impact of the door when closed either gently or strongly and to eliminate noise. The impacting heads of such buffers are, therefore, commonly composed of rubber. The attainment of this principal object has, as a rule, offered no difficulty. But to attain this simple result in a pressed metal construction without complex and more or less expensive additions to the fabrication of the parts and their assembly has been possessed of some difficulty. I have eliminated this difficulty to a large extent.

Most pressed metal constructions involve posts of hollow cross section. I introduce the buffer bodies from the exteriors of these posts through apertures in their exterior or front walls and lay them flatly against the interior side or jamb walls of the posts and I provide a clamping means to hold the bodies firmly yet adjustably against these interior faces of these side walls whereby the outwardly projecting heads may be adjusted at will to engage the closing door to any desired degree, and, yet, when adjusted, are always firmly held in position. The particular structure embodies a post of channel-shaped section in one portion of which at least the walls are offset. I introduce the buffers either through an aperture in the offset or through the bottom of the channel to lie flatly against the interior faces of the side walls of the channel, provide a socket to receive them by securing a sheet metal member to the interior face of the side wall in a position to overlie the body of the buffer, and a simple clamping screw to draw the body of the socket more or less firmly against the body of the buffer.

Still more specifically, the clamping screw passes through the side wall of the channel from the exterior, through the body of the buffer and through the clamping member and the body of the buffer is provided with an elongated slot whereby it may be longitudi-

nally adjusted without interference with the clamping screw.

The drawings show this embodiment of my invention.

Fig. 1 is a side elevation of a motor car body;

Fig. 2 shows the buffer of my invention applied to the doors of this car which is of the sedan type, above the window sills, the section being taken on lines 2—2 of Fig. 1;

Fig. 3 shows my invention as applied to the same doors below the window sills, the section being taken on lines 3—3 of Fig. 1; and

Fig. 4 is a sectional elevation taken on lines 4—4 of the application shown in Fig. 2.

The sedan body in connection with which my invention is illustrated is provided with two doors 10 and 11 respectively which close toward each other upon an intermediate door post commonly known as the B and C post and so designated in this connection. In closed body vehicles, there are commonly used two buffer structures, one near the top of the door and one near the bottom of the door and it is so in this case, the upper one being illustrated in Fig. 2 and the lower one in Fig. 3.

Referring first to the upper structure, it will be seen that the B and C post is of channel cross section presenting inwardly of the body of the car. It comprises an outer or bottom wall 12 and channel side walls 13 and 14 respectively. Projected through aperture 14' in the bottom wall 12 or, at least, in the corners between the bottom and side walls of the channel section, are buffer bodies 15, one on each side, extending interiorly of the hollow of the post and lying flatly against the repetitive side walls 13 and 14 of the channel section. These buffer bodies are substantially flat, yet sufficiently thick to give adequate mechanical strength and elastic absorption of the energy of the door when the bodies are struck by the door. Externally, the bodies are provided with heads 16 of enlarged section projecting laterally beyond the side walls 13 and 14 and forming with the body proper 15 shoulder 17 which abuts the edges of the side walls surrounding the apertures 14'. The heads 16 are, moreover, given a shape in substantial conform-

2
ance with the angles between the jamb rails 18 of the door and their overlapping flanges 19 which directly engage the heads of the buffers when the doors are closed. The 5 heads take the brunt of the buffer action and it is they rather than the bodies 15 proper which require that adjustment of cross-section and length which gives them the proper degree of resilience and resistivity. In- 10 teriorly of the posts, the bodies 15 are provided with elongated slots 19' permitting them to be projected outwardly of the post to adjust the heads 16 to any degree toward and from the outside of the post to vary 15 the range of the buffer action and the resiliency and gradation thereof. Projected through the slot from the exterior of the jamb wall of the post is a clamping screw 20 threaded into an interior nut 21 which 20 confines between itself and the body of the buffer a metal clamping plate 22. The adjusted buffer may by this means be clamped firmly in place against the interior wall of the post. In this embodiment, the plate 22 25 is constituted by the upper end of an angle clip 23 welded by a bottom flange 24 to the interior side wall of the post, so that the upper end is flexibly related to the lower and, therefore, yieldingly related to the 30 clamping screw 20 and nut 21.

This structure possesses the simplicity, cheapness and effectiveness sought for to a remarkable degree.

The structure embodied in the lower buffer outlined in Fig. 3 is essentially similar except that the side walls 13 and 14 of the lower length of the post are offset at 25 to form outwardly presenting shoulders for co-operation with the door and its appurtenances, and the jamb rails 18 of the door are correspondingly offset at 26. The buffer bodies are projected through the offset portions of walls 13 and 14 and their heads lie between offsets 25 and 26 of the posts 40 and doors respectively. Still further, in this case, the clamping plates 22 are comprised of offsets in the inner lining 27 of the post, this lining having sufficient flexibility to yieldingly relate the portions 22 to the 45 clamping screw 20 and the nut 21 which 50 nuts, it may be remarked, are fixed to the

clamping plates so as not to require their being interiorly held while the buffers are adjusted.

I have shown but one embodiment of my 55 invention, and it needs be said that it is capable of other embodiments containing modifications introduced to the end of greater efficiency, to accommodate the structure to various forms of posts and correspondingly, 60 various forms of doors, and for other reasons, all without departing from its generic spirit.

The annexed claims should cover all such 65 embodiments.

What I claim is:

1. In a device of the class described a pressed metal door post having an offset jamb wall of single sheet metal thickness, a buffer block projecting through an aperture 70 in the offset and lying flatly against the inner surface of said jamb wall, and means clamping the body against said inner surface.

2. In a device of the class described a 75 pressed metal hollow door post having a rabbeted jamb wall, a headed buffer block projected through an aperture in the rabbet to lie flatly against the inner surface of the post with its head nested in said rabbet, and 80 means firmly clamping the body against said inner surface.

3. In combination, a pressed metal door post having a rabbeted jamb wall, a resilient buffer block projecting through an aperture 85 in the rabbet and lying flatly against the inner surface of said door post, and a flexible plate attached to said door post and embracing said buffer block to retain the latter in position. 90

4. In combination, a pressed metal door post, a plate attached to the inner surface thereof, the main body of said plate being laterally spaced from the jamb wall of the post, and a resilient buffer block having its 95 head disposed exteriorly of said door post and its main body disposed in the space between said jamb wall and said plate laterally spaced therefrom.

In testimony whereof I hereunto affix my 100 signature.

JOSEPH LEDWINKA.
